UNITED STATES PATENT OFFICE.

FREDERICK W. GEHRKE, OF PHILADELPHIA, PENNSYLVANIA, ASSIGNOR TO THE HORN & BRANNEN MANUFACTURING CO., OF PHILADELPHIA, PENNSYLVANIA, A CORPORATION OF PENNSYLVANIA.

DESIGN FOR A GLOBE FOR LIGHTING FIXTURES.

Application filed June 16, 1922. Serial No. 2,703. Term of patent 7 years.

To all whom it may concern:

Be it known that I, FREDERICK W. GEHRKE, a citizen of the United States, and residing at Philadelphia, in the county of Philadelphia and State of Pennsylvania, have invented a new, original, and ornamental Design for a Globe for Lighting Fixtures, of which the following is a specification, reference being had to the accompanying drawing, forming part thereof.

The figure is a perspective view of a globe for lighting fixtures showing my new design.

I claim:

The ornamental design for a globe for lighting fixtures, as shown.

FRED. W. GEHRKE.
